(57) **CLAIM**

The ornamental design for a golf glove, as shown and described.

DESCRIPTION

FIG. 1 is a back thumb-side perspective view showing our new design;

FIG. 2 is a plan view of the back thereof;

FIG. 3 is a plan view of the front thereof;

FIG. 4 is a thumb-side elevation view thereof;

FIG. 5 is a small-finger-side elevation view thereof;

FIG. 6 is an elevation view of the closed fingertip end thereof; and

FIG. 7 is an elevation view of the open wrist end thereof;

FIG. 8 is a back thumb-side perspective view showing another embodiment of our new design;

FIG. 9 is a plan view of the back thereof;

FIG. 10 is a plan view of the front thereof;

FIG. 11 is a thumb-side elevation view thereof;

FIG. 12 is a small-finger-side elevation view thereof;

FIG. 13 is an elevation view of the closed finger-tip end thereof; and,

FIG. 14 is an elevation view of the open wrist end thereof.

In FIGS. 1–7 the broken lines represent stitching and form no part of the claimed design. The different shading shown in regions of the back and regions of the front thereof indicates a contrast in appearance between the respective regions.
